UNITED STATES PATENT OFFICE.

ERWIN MARSHALL, OF CANTON, OHIO.

DESIGN FOR A VAPORIZER FOR INCANDESCENT LAMPS.

SPECIFICATION forming part of Design No. 35,189, dated October 15, 1901.

Application filed September 3, 1901. Serial No. 74,252. Term of patent 3½ years.

To all whom it may concern:

Be it known that I, ERWIN MARSHALL, a citizen of the United States, residing at Canton, in the county of Stark and State of Ohio, have invented and produced a new and original Design for a Vaporizer for Incandescent Lamps, of which the following is a specification, reference being had to the accompanying drawings, forming part thereof.

Figure 1 is a side elevation, and Fig. 2 is a bottom or under side view.

As shown in the drawings, the leading or material feature of my invention consists of a straight plain body 1, having located at one end thereof the spherical head 2, from which spherical head extends the flange 3, which flange is provided with a plain end 4 and the side faces 5. From the plain face 4 extends the bar 6, which bar extends in a straight line to about the point 7 and then extends at an angle to the point 8, from whence it is curved to the point 9 and then extends in a straight line to the point 10, and from said point 10 it is curved

to the point 11 and extends in a straight line to the point 12, and again extends in a straight line at an angle, and its extreme outer end is provided with the enlarged portion 13. The bar 1 is provided upon the opposite end from that of the spherical head with the annular flange 14 and the collar 15. The bar 6, together with its different bends and angles, extends at an angle to the bar 1, substantially as shown in Fig. 1.

Having fully described my invention, what I claim as new, and desire to secure by Letters Patent, is—

The design for a vaporizer for incandescent lamps as herein shown and described.

In testimony that I claim the above I have hereunto subscribed my name in the presence of two witnesses.

ERWIN MARSHALL.
